UNITED STATES PATENT OFFICE.

SARAH K. ALLISON, OF MACOMB, ILLINOIS.

FREEZER.

Application filed January 18, 1922. Serial No. 530,093.

To all whom it may concern:

Be it known that SARAH K. ALLISON, a citizen of the United States of America, residing at Macomb, in the county of Mc-
5 Donough and State of Illinois, has invented new and useful Improvements in Freezers, of which the following is a specification.

The object of the invention is to provide a simple and efficient construction of domestic freezer which is convertible to form a cooking utensil and wherein provision is made for the economical use of the ice or other freezing agency; and with this object in view the invention consists in a construction and combination of parts of which the preferred embodiment is shown in the accompanying drawings, wherein:—

Figure 1 is a vertical central sectional view of an apparatus embodying the invention.

Figures 2 and 3 are transverse sectional views on the planes indicated respectively by the lines 2—2 and 3—3 of Figure 1.

Figures 4 and 5 are detail views of dashers adapted respectively for mechanical and manual operation.

The apparatus consists essentially of an outer receptacle 10 fitted with a removable cap or cover 11 connected with the upper 20 edge of the receptacle by a slip joint 12, said receptacle being provided near its upper edge with an offset forming an interior shoulder 13, an inner receptacle 14 arranged concentrically in the outer receptacle and spaced at its side walls and bottom therefrom and provided with a removable cap or cover 15 having a slip joint engagement at 16 with the upper edge of the receptacle which is provided near the upper edge of its 30 side wall with an offset forming an exterior shoulder 17, and an annular screen 18 seated upon the inner shoulder of the outer receptacle held by clasps or a spring clasp and forming at its inner edge a bearing for the 40 exterior shoulder of the inner receptacle.

The joint between the inner receptacle and its removable cap or cover is preferably supplemented by latches 19 to prevent accidental disengagement thereof and the inner 50 receptacle is provided with a pivotal bail or handle 20 to facilitate the removal thereof from the outer receptacle and adapted under normal conditions to be housed within the cap or cover of the outer receptacle. Said 55 outer receptacle is also provided with a similar bail or handle 21 and a supplemental

seat for the inner receptacle is provided in the outer receptacle below the plane of said screen 17 and consisting in the construction illustrated of a band 22 and a zigzag spacing strip 23. The space between the walls of the inner and outer receptacles constitutes an ice chamber and the inner receptacle is preferably provided with an axial circulating tube or drum 24 in communication at its 60 lower end with the ice chamber and provided at its upper end with a perforated screen 25. A cap 26 is also removably fitted upon the upper end of said circulating tube or drum.

At its center the cap or cover of the outer receptacle is provided with a neck 27 fitted with a removable plug or stopper 28, and the cap or cover of the inner receptacle is provided with a similar neck 29 extending 70 upward and telescoping into the neck of the cap or cover of the outer receptacle so that the plug or stopper 28 serves to close the same. Furthermore a ventilating device is provided for the outer receptacle consisting 75 of perforations 30 in the top of the outer receptacle and adapted to be either exposed or covered by a slide valve 31 accessible from the exterior of the apparatus by means of a knob 32.

The stopper or plug 28 fitted as above described in the cap or cover of the outer receptacle serves as a support for a dasher or beater arranged within the inner receptacle and provided in the construction illustrated 80 with a threaded stem 33 extending through a threaded opening 34 in said plug or stopper and carrying radial blades 35 which support one or more beater heads 36. In the construction illustrated in Figures 1 and 4 85 wherein provision is made for rotation of the dasher or beater by means of a crank 37 or other mechanical means, actuatable if desired by power, two beater heads are employed in vertically spaced relation for operation in the inner receptacle between the side wall thereof and the axially disposed circulating tube or drum 24, and each head consists of inner and outer annular bands 38 and 39 connected by a zigzag spacing or 90 filler strip 40 so that in the combined rotary and vertical movement of the dasher a comparatively violent agitation of the liquid contents of the inner receptacle is produced. The radial wings of the dasher preferably 105 consist of looped rods as shown.

In the simpler form of dasher shown in

5 detail in Figure 5 the construction contemplates the use of only one dasher head 36^a carried by the rods constituting the radial blades 35^a, and the threaded stem 33^a is fitted with a hand grip 41 secured to the stem by a set screw 42 or its equivalent.

Obviously, assuming that the receptacles are made of suitable materials, the removal of the dasher will convert the apparatus into 10 a cooking vessel adapted for use as a double boiler similar in general construction to that disclosed in my co-pending application No. 530,094 filed of even date herewith and in which those features common to the two 15 structures are claimed,—the claims of this application being devoted particularly to those features of the construction which adapt it particularly for use as an ice cream freezer or a churn wherein the inner receptacle is designed for containing the liquid or material to be treated while the compartment or chamber formed by the space between the inner and outer receptacles is 20 adapted for the reception of a tempering or freezing agency according to the purpose for which the apparatus is being used.

Having described the invention, what is claimed as new and useful is:—

1. In a freezer, a receptacle provided with 30 a removable cover having a flanged opening, a plug closing the flanged opening, a cylindrical drum rising axially from the bottom of the receptacle and open at its lower end and provided at its upper end with a cover 35 closed screen, and a dasher telescoping the drum and operable in the receptacle and having a stem threaded for engagement in said plug to provide for combined rotary and reciprocating movements in the receptacle.

2. A freezer comprising a receptacle, a drum rising axially from the bottom of the receptacle and open at its lower end, a cover

for said receptacle, a plug for the cover, and a dasher having beater heads telescoping 45 the drum and provided with a stem mounted for operative engagement with and through the plug to provide for combined rotary and reciprocating movements of the dasher within the inner receptacle. 50

3. In a freezer, the combination with a receptacle, including a cover with an up-standing tubular neck having a plug for closing the neck, of a drum rising axially from the bottom of the receptacle and open 55 at its lower end, the upper end of the drum terminating a substantial distance below the neck and provided with a cover closed screen, and a dasher telescoping the drum and comprising a frame and beater heads, the frame of the dasher having a stem mounted for operative engagement with and through the plug to provide for combined rotary and reciprocating movements of the dasher within the inner receptacle. 60

4. In a freezer, the combination with inner and outer receptacles, the former being supported in spaced relation within the latter and provided respectively with removable covers correspondingly spaced one within 70 the other, the inner cover having an up-standing tubular neck fitting through the top wall of the outer cover, of a cylindrical drum rising axially from the bottom of the inner receptacle with its lower end open in 75 communication with the outer receptacle, the upper end of the drum terminating a substantial distance below and axially with the neck and provided with a cover closed screen, and a common plug fitting within the neck, thereby closing the same and the outer cover. 80

In testimony whereof she affixes her signature.

SARAH K. ALLISON.
